(57) **CLAIM**

The ornamental design for a sole for footwear, as shown and described.

DESCRIPTION

1. Sole for footwear

1.1 : Left

1.2 : Right

1.3 : Perspective

1.4 : Perspective

1.5 : Perspective

1.6 : Bottom

Design of a shoe sole with individually prolonged toe areas that reach beyond the front of the upper shoe; as indicated by the broken lines in the reproductions, no protection is sought for the upper shoe as such.

1 Claim, 6 Drawing Sheets
